UNITED STATES PATENT OFFICE.

MICHAEL S. O'NEIL, OF ROCK ISLAND, ILLINOIS.

SHAPER ATTACHMENT FOR ROUNDING WOODEN POLES.

SPECIFICATION forming part of Letters Patent No. 268,527, dated December 5, 1882.

Application filed July 20, 1882. (No model.)

To all whom it may concern:

Be it known that I, MICHAEL S. O'NEIL, a citizen of the United States, residing at Rock Island, in the county of Rock Island and State of Illinois, have invented certain new and useful Improvements in Shaper Attachments for Rounding Wooden Poles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to shapers for rounding up wagon, sulky, and cultivator poles and all other kinds of straight timber. Such poles and timber are now shaped or rounded by means of a form of hard wood, the shape and length of the stick to be rounded rabbeted out on the upper and outside corner of the form as far as it is desired to round the pole. This method calls for the attendance and services of two operatives in rounding each pole.

The object of the present invention is to abolish the hard-wood form altogether and to replace it by an attachment to the shaper which requires but one operative.

In the accompanying drawings, wherein like letters refer to like parts, Figure 1 is a side perspective view of my attachment with all its parts, and Fig. 2 a similar view taken from the opposite side.

A is a metal casting or thin slab of hard wood, which is bolted to the table of an ordinary pole-shaping machine by bolts passing through the eye *a* and the slot *a'*, the slot permitting the attachment to be adjusted nearer to or farther from the cutter-head of the shaper, as desired. This cutter-head revolves in the semicircular space marked B. Gages C C, with slot-pieces *c c'* and slides *c' c''*, are made adjustable by means of bolts and nuts *c² c³*. Rollers D D, with arms *d d'*, axles *d' d''*, and washers *d² d³*, are made adjustable up and down by bolts or screws *d³ d⁴* operating in short

standards *d⁴ d⁵*. Bearing-springs E E are made adjustable by bolts and nuts or screws *e e'* working in the flanges *e' e''*.

To operate the attachment, adjust the eye *a* and slot *a'* upon the shaper-table, so as to bring the cutter-head as far as necessary into the semicircular space B. Then adjust the gages C C and the bearing-springs E E with reference to the width of the pole to be rounded. Then adjust the rollers D D with reference to the thickness of the pole to be rounded. Then insert the pole or stick of timber between the arms of the roller D, which is over the larger of the two gages C, and push it along as far as the side needs to be rounded. The rollers D D will hold it down to the bed or floor of the attachment, the bearing-springs E E will hold it firmly against the cutter-head, which planes and rounds it, and the gages C C will keep it in line while operated upon by the cutter. When pushed and rounded as far along its length as necessary, let the operator at the end of the pole jerk or press it sidewise against the springs E E, which will then yield and open and allow the pole to be withdrawn without touching the revolving cutter-head. The other side of the pole can then be presented to the cutter-head and rounded in the same way, and the pole again withdrawn.

Having thus described my invention, what I claim as new and original, and desire to secure by Letters Patent, is—

A pole-shaving machine with bed plate having adjustable gages, as C, on the side of the bed toward the cutter-head, spring-arms, as E, on the side opposite the cutter-head, to hold work against the cutter-head, and bearing-rolls, as D, borne on adjustable arms above the bed-plate, substantially as shown and described.

In testimony whereof I affix my signature in presence of two witnesses.

MICHAEL S. O'NEIL.

Witnesses:

RUSSELL H. CURTIS,
M. EDWARD SWEENEY.
